Attorney

UNITED STATES PATENT OFFICE

MARIANO BALSAMO, OF ST. LOUIS, MISSOURI, ASSIGNOR TO FRUIT SUPPLY COMPANY, OF ST. LOUIS, MISSOURI, A CORPORATION OF MISSOURI

BASKET

Application filed June 14, 1929. Serial No. 370,778.

This invention relates to baskets, and with regard to certain more specific features to covered baskets for shipping produce and the like.

5 Among the several objects of the invention will be noted the provision of a basket for shipping produce and the like and having a cover which will be positively aligned so as to prevent damage to produce being shipped therein; the provision of a basket of the class described which has no internal sharp corners which might tend to damage its contents; and the provision of a basket of the class described which may be simply and inexpensively manufactured. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

25 In the accompanying drawing, in which are illustrated two of the various possible embodiments of the invention,

Fig. 1 is a perspective view showing a basket with my invention applied thereto;

30 Fig. 2 is a plan view of the basket of Fig. 1 with the improved cover removed;

Fig. 3 is a fragmentary section taken at the rim of the basket of Fig. 1;

Fig. 4 is a side elevation of another form 35 of basket showing the invention applied thereto; and,

Fig. 5 is a fragmentary section similar to Fig. 3, but referring to the Fig. 4 form of the invention.

40 Similar reference characters indicate corresponding parts throughout the several views of the drawing.

Referring now more particularly to Fig. 1, there is illustrated at numeral 1, a body portion of produce basket of the wooden-slat type provided with girth bands or hooks 3 and 5. The upper edge 7 of the upper band 3 is approximately flush with the upper ends or edges of the slats 9 which form the bottom 50 and side walls of the basket.

Heretofore a basket of this type also provided an inner band similar to the outer band 5 whose upper edge was also flush with the edges 7 and 9. After the basket was filled with produce, the lid thereof was placed over the produce with the periphery resting upon the edges of the band 7, slats 9 and the extra inner band, not shown herein but above referred to. The result was that during transit, the lid, which was held down by resilient means, often slipped and the edge thereof did considerable damage to the produce in the basket, especially the top layer thereof.

I have overcome the above difficulties by providing an inner hoop or flange 11, preferably wooden, (see Fig. 3) about and above the mouth of the basket, having a V-shaped cross section with the pointed portion directed downwardly. This flange 11 is held with the outer band 5 at the upper edge of the slats 9 by means of clamping staples 13, at suitable intervals.

The purpose of downwardly tapering the flange 11 is to prevent a sharp corner between its lower edge and the inner surface of the basket such as existed when an inner flush band, similar to the band 5 was used inside of the mouth of the basket. It will be seen that the right-angular form of the lower edge of such a band would and did result in a sharp inner corner, against which the produce would scrape and become injured. My tapering construction avoids this type of injury. At the same time, the tapering section is extended upwardly to form a relatively heavy rim 15 extending above the flush edges 7, 9.

I provide the lid 17 of the basket with a depending flange 19 at its periphery. The diameter of the flange 19 is slightly larger than the diameter of the upwardly extending flange 11 and about the same as the diameter of the flush portions 7, 9. The result is that a telescoping engagement may be effected between the inner rim 11 and the outer rim 19, said outer rim 19 coming to rest on the flush edges 7, 9, of the band 5 and slats 9 respectively. The depth of the depending flange or rim 19, in relation to that of the inner rim 100

or hoop 11, is such that the top edge of the inner rim is disposed so closely adjacent the under surface of the lid 17, when the rim 19 rests on said edges 7, 9, as to prevent substantial exposure of the top edge corners of the rim 11 to the produce. The result is that there is formed around the upper, inner angle of the closed basket a smooth contour without protruding angular portions which might damage the produce or the like located within the basket were it permitted to remain as it was in the prior basket.

Fig. 1 shows how the upper mouth of the basket is provided at opposite sides with two upwardly extending handles, 21 adapted to receive therethrough a springing slat 23 for holding down said lid 17. It has been this type of springing holder which has heretofore permitted the lid to creep in transit when no flanges were used, whereby damage was caused, as well as by the sharp corner at the inside rim of the basket.

In Figs. 4 and 5 is shown an alternative form of the invention applied to a wire basket. In this form, the basket comprises a network of wires 25 interwoven and connected with suitable bands 27 for retaining or maintaining the shape of the basket.

In this modification, I prefer that the inner band 11 be double tapered, both up and down, and that it be stopped flush with the upper edge 29 of the upper, outer band 27. Instead of aligning or telescoping the cover or lid, I prefer to extend the wires 25 upwardly as shown at numeral 31, either at every wire or at suitable intervals so that the outer depending flange of the cover 17 can be made to telescope with the resulting, upwardly extending series of pins or fingers formed for guiding purposes.

It is to be understood that instead of extending the wires 25, they may be cut off at the upper edges of the rims 27, 11, and separate pins may be driven into the upper wooden edges, or between them, to form a series of telescoping fingers adapted to prevent side slip of the cover.

It is to be understood that other means may be used for effecting the telescoping guide for a flange formed on the outer periphery of the cover. However, I deem the above preferred method to be the one most readily adapted to actual practice.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall be interpreted as illustrative and not in a limiting sense.

65 I claim:

1. A basket of the class described having a top edge, a hoop surrounding the basket and substantially flush with the top edge, a hoop inside the top edge and extending above the same, said inside hoop being tapered downwardly and outwardly so as to eliminate a bottom edge corner against which the produce in the basket might otherwise rest and become injured, means binding said hoops together with the basket wall therebetween, and a lid member so juxtaposed adjacent the top of the inside hoop as to prevent substantial exposure of the top edge corners of said inside hoop to said produce, said lid member having a flange extending downwardly outside of the inside hoop.

2. A basket of the class described having a top edge, a hoop surrounding the basket and substantially flush with the top edge, a hoop inside the top edge and extending above the same, means binding said hoops together with the basket wall therebetween, the inside hoop being tapered downwardly and outwardly so as to eliminate a bottom edge corner against which the produce contained in the basket might otherwise rest and become injured, and a lid member so juxtaposed adjacent the top of the inside hoop as to prevent substantial exposure of the top edge corners of said inside hoop to said produce, said lid member having a flange extending downwardly outside of the inside hoop, the lower edge of the flange engaging the substantially flush top edges of the basket and outside hoop.

In testimony whereof, I have signed my name to this specification this tenth day of June, 1929.

MARIANO BALSAMO.
